UNITED STATES PATENT OFFICE.

LOUIS KUNOWSKY, OF WINONA, MINNESOTA.

REFRIGERATOR.

1,188,950.

Specification of Letters Patent. Patented June 27, 1916.

Application filed October 15, 1915. Serial No. 55,990.

To all whom it may concern:

Be it known that I, LOUIS KUNOWSKY, a citizen of the United States, residing at Winona, in the county of Winona and State of Minnesota, have invented certain new and useful Improvements in Refrigerators, of which the following is a specification.

This invention relates to refrigerators and more particularly to that class of such devices provided with a top ice box and adapted to cool the contents through the medium of a lower food receptacle.

The primary object of this invention is the provision of a device of the character set forth with removable means for supporting the ice in proper position and removable side walls for the ice receptacle thereby insuring a sanitary ice receptacle.

With the foregoing and other objects in view as will hereinafter appear from time to time, this invention consists in the peculiar combination and arrangement of the various related parts of a refrigerator as herein described and more particularly set forth in the appended claims.

Referring to the drawings forming a portion of this specification and illustrating the preferred embodiment of construction and in which the same reference characters indicate the same parts wherever used, Figure 1 is a transverse section through a device embodying the invention; Fig. 2 is a longitudinal section therethrough; Fig. 3 is a section on line 3—3 of Fig. 2; Fig. 4 is a detail perspective of the method of locking the sheathing means; and Fig. 5 is a detail perspective of one of the removable ice box wall members.

6 designates a framework formed of wood or other suitable material and constructed to form rectangular frames corresponding to the size of the various sides of the receptacle. Placed over both the inner and outer sides of this framework is a suitable sheet of sheathing material 7 preferably of heat insulating cardboard or the like and extending the entire length of the framework and corresponding in size to its respective wall. Outside of both of the sheets 7—7 is provided a metal sheathing 8 which may be stamped to form panels or other suitable ornamentations 9, the cardboard insulation following the contour of the metal and leaving an air space between the two sheets of cardboard which are spaced apart by the framework 6. The sheet metal 8 is provided at each angle joint with a lap joint 9' formed by bending

the abutting sheets of metal, one over the other and lapping the same to form a tight joint. The receptacle is provided with the usual doors 10—10. The interior of the box is provided at its upper end with a series of plates 11 fastened to the interior wall and spaced therefrom by means of washers 12. Adapted to be supported by the members 11 are a plurality of members 13, one of which is shown in separated relation in Fig. 5 which are provided with upper hook members 14 adapted to engage the members 11 and to support the members 13 by engagement therewith. Each of the members 13 is provided with an upturned portion 15 at its lower end adapted to abut against the interior wall of the box and prevent the members 13 from touching the interior walls. 75 The three members 13 are locked together by means of a sliding joint comprising a socket 16 upon each of the two end members and a plurality of tongues 17 upon the rear member adapted to engage the sockets 16. Each 80 of the members 13 may be removed by upward pressure to release the hook portion 14 from the rear of the support 11 and the corresponding sockets and tongues 16—17. The rear member 13' is provided at its 85 lower extremity with a bar 18 corresponding to the support 11 and similarly spaced from the member 13' which supports by means of a plurality of hooks 19 connected by a cross-bar 20, a corrugated plate 21 90 adapted to receive the ice to be placed in the box. Opposite the member 18 the interior wall of the box upon the partition 22 between the bars 10—10 is provided with a similar supporting bar 23 which supports by 95 means of a plurality of hooks 24 a drip pan 25 having a piping extension 26 extending therefrom and having a plurality of additional supporting hooks 27 reversely curved from the rear of the drip pan, the said 100 hooks 27 engaging the support 18 of the member 13'. As an additional support for the member 21, it is provided with a plurality of downturned legs 28 formed integral with the hooks 19 adapted to rest 105 against the drip pan 26 at a portion below the supporting hooks 24, in order that the weight of the ice may be equalized between the supports 19 and legs 28. The piping extension 26 communicates with a larger member 29 which in turn communicates with the usual drip outlet 30 extending through the bottom of the box. 110

When it is desired to clean the box, the

member 29 is lifted out of the drip outlet 30 and removed, whereupon the drip pan 25 may be removed by disengaging the hooks 27 from the support 18 and the hooks 24' 5 from the corresponding support 23 and the drip pan removed through the lower of the doors 10—10. The ice holding pan may now be removed by lifting the hooks 19 from off of the support 18 when the three members 10 13, 13 and 13' may be removed by exerting upward pressure upon the lower portions thereof and disengaging the extensions 14 from the plurality of supports 11 and the tongues 17 from the sockets 16, whereupon 15 the different parts may be separately cleaned and then reassembled in the reverse order, as heretofore described.

The metal sheathing serves to provide a sanitary interior and exterior for the box 20 and the cardboard internal sheathing upon both sides of the wooden framework serves to provide an effectual air chamber and to thoroughly insulate the box from the outer air.

25 Without further analysis, the foregoing will so fully reveal the gist of this invention that others can by applying current knowledge readily adapt it for various applications without omitting certain features that, 30 from the standpoint of the prior art, fairly constitute essential characteristics of the generic or specific aspects of this invention, and therefore such adaptations should and are intended to be comprehended within the 35 meaning and range of equivalency of the following claims.

I claim:

1. In an ice box, the combination with a plurality of walls, of supports on said walls, a plurality of removable interlocking supplemental wall members carried by said supports, an ice carrying member mounted on one of said supplemental wall members, an additional support in the interior of said 40 box, a drip pan supported by said additional support and one of the supplemental wall members, and means between the drip pan and the ice carrying member adapted to additionally support said member.
2. In an ice box, the combination with a plurality of walls, of supports thereon, a plurality of supplemental side wall members provided with flanges to engage said supports, a supplemental rear wall member having a flange adapted to engage the support upon the rear wall, the side wall members having sockets, additional flanges upon the rear supplemental member adapted to slidably engage the sockets to interlock there- 55 with and means carried by each of the supplemental members to space the same from the box walls.

3. In an ice box, the combination with a plurality of walls, of supports thereon, a plurality of supplemental wall members carried thereby, a support upon the rear one of said supplemental members, an ice carrying member carried by the rear supplemental wall support, a drip pan supported between the rear supplemental wall support and one 65 of the box wall supports and adapted to sustain the front end of the ice carrying member, and means for conveying the drip water therefrom.

4. In an ice box, the combination with a plurality of walls, of supports thereon, supplemental wall members carried by said supports, a support on the rear one of the supplemental members, an ice carrying member, hooked members upon the ice carrying member 80 engaging the rear supplemental wall support, a drip pan, hooked members thereon engaging the rear supplemental wall support and one of the box wall supports, legs on said ice carrying member adapted to engage the drip pan to be supported thereby, and means for conveying the drip water from said pan.

5. In an ice box, the combination with a plurality of walls, of supports thereon, supplemental wall members carried by said supports, a support on the rear one of the supplemental members, an ice carrying member, hooked members upon the ice carrying member 90 engaging the rear supplemental wall support, a drip pan, hooked members thereon engaging the rear supplemental wall support and one of the box wall supports, the hooked members engaging the rear supplemental wall support being reversely 95 curved to permit of the proper length of the drip pan.

6. In an ice box, the combination with a plurality of walls, of supports thereon, supplemental wall members carried by said supports, a support on the rear one of the supplemental members, an ice carrying member, hooked members upon the ice carrying member 100 engaging the rear supplemental wall support, a drip pan, hooked members thereon 110 engaging the rear supplemental wall support and one of the box wall supports, legs on said ice carrying member adapted to engage the drip pan to be supported thereby, said legs being formed integral with the 115 hooked members on said ice carrying member and extending thereunder.

In testimony whereof I affix my signature in presence of two witnesses.

LOUIS KUNOWSKY.
